UNITED STATES PATENT OFFICE.

JOSEPH J. KWIS, OF FINDLAY, OHIO, ASSIGNOR TO THE ADAMS BROTHERS COMPANY, OF SAME PLACE.

POWER DEVICE FOR PUMPING WELLS.

SPECIFICATION forming part of Letters Patent No. 591,283, dated October 5, 1897.

Application filed May 27, 1897. Serial No. 638,356. (No model.)

To all whom it may concern:

Be it known that I, JOSEPH J. KWIS, of Findlay, in the county of Hancock and State of Ohio, have invented a new and Improved 5 Power Device for Pumping Wells and for Similar Purposes, of which the following is a full, clear, and exact description.

The object of the invention is to provide a power device especially adaptable for pumping oil-wells, but which may be employed for analogous purposes, the construction of said power device being such that a practically direct connection can be made between the engine or other motor used and the mechanism 10 employed for operating the surface-rods in oil-pumping machinery, the motion being so communicated through the said driving-wheel as to prevent any twisting strain whatever on the shafts. 15 Another object of the invention is to provide a device of the character described which will be compact, simple, and durable, as well as economic, and capable of being secured to a single timber, if necessary, thus dispensing 20 with a complicated foundation.

The invention consists in the novel construction and combination of the several parts, as will be hereinafter fully set forth, and pointed out in the claims.

Reference is to be had to the accompanying drawings, forming a part of this specification, in which similar characters of reference indicate corresponding parts in all the figures.

Figure 1 is a side elevation of the improved device. Fig. 2 is a plan view thereof. Fig. 3 is a partial vertical section through the driving-wheel for the surface rods. Fig. 4 is a section through the rim portion of said driving-wheel, illustrating a mechanism whereby 35 three or more surface rods may be connected at given points on the drive-wheel. Fig. 5 is a vertical section through the drive-wheel, the periphery whereof is constructed to receive at various points two or more surface-rods. Fig. 6 is a vertical section taken substantially on the line 6 6 of Fig. 7. Fig. 7 is a plan view of an extension device for the drive-wheel. Fig. 8 is a section taken on the line 8 8 of Fig. 9. Fig. 9 is a plan view of 45 another form of extension for the drive-wheel. Fig. 10 represents, respectively, a side eleva-

tion and a sectional view of a modified form of pin used in connection with the drive-wheel. Fig. 11 is a side elevation of the pin usually employed in connection with said 55 drive-wheel. Fig. 12 is a side elevation of a further modification of the pin, and Fig. 13 is a section on the line 13 13 of Fig. 12.

A represents a beam which constitutes a bed for an engine B, the type shown being 60 the ordinary oil-field engine. The power-shaft 10 of the engine is shown as provided at one of its ends with a pinion 11, and this pinion meshes with the teeth of a power-transmitting wheel 12, shaft 13 of which is 65 journaled in suitable bearings 14, one of which is shown on the beam or foundation A and the other upon a suitable sill A', near the main foundation A. A pitman 15 is connected with the power-transmitting wheel 70 through the medium of a ball wrist-pin 16.

The drive-wheel C is shown in a horizontal position and as mounted to turn upon a vertical shaft 17, carried by the beam or foundation A. The drive-wheel is provided with a 75 circumferential central continuous channel 18, and above and below said channel the outer rim-surface of the wheel is provided with recesses 19, usually of angular formation, forming a number of teeth around the 80 aforesaid outer surface of the rim of the wheel, and when occasion may demand similar recesses 20 may be produced in the inner face of the rim of the wheel, as shown in Fig. 2.

The drive-wheel C is adapted to carry rods 85 D, which in all pumping machinery are usually designated "surface" rods, and these rods are attached to the pumping-jacks or any other device at the well provided for removing the fluid. The rods D are pivotally 90 connected with the rim of the wheel in such manner that as the wheel turns adjacent rods will not interfere with each other.

The surface rods are usually connected with the drive-wheel by causing pins 22 to be 95 passed through the rods, which pins are located in the recesses 19 on the wheel, as shown particularly in Figs. 4 and 5. The pins are held in position on the wheel by means of clamps 23 or their equivalents 100 passed around the pins and horizontally through the rim portion of the wheel. In

Fig. 5 I have illustrated a pin 22 as projecting above and below the rim of the drive-wheel, so that one surface rod may be pivoted on the pin at the channel 18 in the wheel, another above the rim, and a third below the rim. In Fig. 4 the rim of the wheel is enlarged and is provided with teeth 24, intermediate of the top and bottom teeth, and in this construction of the rim of the wheel two annular recesses 25 are formed. It is evident that under this latter construction a larger number of surface rods may be connected with each pin than under the construction illustrated in Fig. 5. The pitman 15, connected with the power-transmitting wheel 12, is likewise connected by means of the ball wrist-pin 16^a with a horizontal extension 21 from the rim of said drive-wheel, as shown particularly in Figs. 1, 2, and 3. The drive-wheel, through the action of the power-transmitting wheel, is given alternately a forward and a backward movement. The pins are connected to the drive-wheel through the medium of bolts or clips 23^a, which are shown as U-shaped, but may be otherwise shaped, as desired. These bolts or clips after passing around the pin are carried through the rim of the wheel.

In Figs. 6 and 7 I have shown brackets which may be utilized to provide for surface rods being attached to the drive-wheel at points beyond the rim proper. The bracket shown in Figs. 6 and 7 consists of a top and bottom plate 26, connected by two pins or posts 27, said plates being attached to a curved body 28, extending above and below the plates and provided with teeth 29, which are of such formation that they may enter the spaces between the teeth on the outer surface of the rim of said drive-wheel. In Figs. 8 and 9 I have shown a modified form of the bracket illustrated in Figs. 6 and 7. This modification of the bracket consists of a curved body 30, and from the concaved surface of the body 30 teeth 32 are projected, which may enter the spaces between the teeth on the rim of the drive-wheel, and upon the outer or convexed face of the body upper and lower horizontal plates 31 are formed, having recesses therein forming teeth, and the teeth formed in the plates 31 correspond to the teeth which are formed on the rim of the drive-wheel and receive between them pins similar to the pins 22, heretofore described, and upon which the surface rods are pivoted.

In Fig. 10 I have illustrated a modified form of the pin. This pin is provided with projections 33, so shaped that they will enter and fit into the recesses or spaces between the teeth on the rim of the drive-wheel or the teeth upon a bracket extension.

It will be understood that instead of the pinion 11, driven by the engine B, meshing directly with the power-transmitting wheel

12 the motion may be communicated from the drive-shaft 10 of the engine to the shaft upon which the power-transmitting wheel 12 is placed or to the wheel direct in any other suitable manner, and that any desired motor may be employed.

It will be understood that bolts similar to the bolts 22^a are utilized for securing the brackets to the drive-wheel and the pivot-pins in the brackets, and also that the recesses 20 on the inner face of the rim may be utilized for securing a bracket or any extension from the drive-wheel to said wheel. In Fig. 2 the extension from the drive-wheel to which the pitman 15 is attached is illustrated as connected in such manner.

I do not confine myself to either form of the driving-wheel C shown. The straps used for attaching the surface rods to the pins 22 may be of any desired length, and any necessary number of bolts may be employed for securing the straps. Each strap 34 is provided with a half-box 35, having an opening to receive the bolt, thus permitting any lost motion caused by wear to be taken up. When the surface rods are of wood, they abut against the boxes 35; but whenever any other material than wood is used a block of wood or any other suitable material may be bolted in between the straps to fit against a box 35.

In Figs. 12 and 13 I have shown another modified form of a pin 22, which is turned from round bar iron or steel and is of enlarged diameter at each side of the center or where the pin does not connect with the surface rods, as shown at 36. Those portions of the enlargements 36 adapted to fit into the drive-wheel are planed off upon two sides, giving these portions of the pin an angular formation, as shown at 37 in Fig. 13. Grooves 38 are produced near the plain surfaces 37 to receive the U-bolts 23.

Having thus described my invention, I claim as new and desire to secure by Letters Patent—

1. In a power device for pumping wells and for similar purposes, the combination, with a drive-wheel having a toothed rim, brackets attached to said rims and pivot-pins adapted to receive surface rods or like devices, secured in the spaces between the teeth on the rim of said wheel and in the said brackets, for the purpose set forth.

2. In a power device for pumps, the combination of a drive-wheel having a toothed periphery, a bracket having teeth adapted to mesh with the teeth of the drive-wheel, a pin held by the bracket, and a surface rod having pivotal connection with the pin.

JOSEPH J. KWIS.
